[57] CLAIM

The ornamental design for a tub for bathing, as shown and described.

DESCRIPTION

FIG. 1 is a perspective view taken from the top and front of a tub for bathing embodying our new design; FIG. 2 is a perspective view taken from the top and right side thereof;

FIG. 3 is a top plan view thereof;

FIG. 4 is a cross-sectional view thereof taken on line 4—4 of FIG. 3;

FIG. 5 is a cross-sectional view thereof taken on line 5—5 of FIG. 3;

FIG. 6 is a cross-sectional view thereof taken on line 6—6 of FIG. 3; and,

FIG. 7 is a perspective view taken from the top and front thereof.

The fragmentary broken line representations of an apron type enclosure in FIGS. 1, 2 and 7 and of pillows in FIG. 7 are for the purpose of illustration only and form no part of the claimed design.
